UNITED STATES PATENT OFFICE.

AUGUST W. WARSEN, OF NEW YORK, N. Y.

CRUSHER.

1,101,480.

Specification of Letters Patent. Patented June 23, 1914.

Application filed October 17, 1913. Serial No. 795,679.

To all whom it may concern:

Be it known that I, AUGUST W. WARSEN, a citizen of the United States, and a resident of New York, borough of Brooklyn, in the county of Kings and State of New York, have invented a new and Improved Crusher, of which the following is a full, clear, and exact description.

The invention relates to crushers of the jaw type; and the object thereof is to provide a simple, strong, and inexpensive crusher by means of which material can be crushed to varying sizes, not exceeding a predetermined maximum.

I obtain the above object by providing a frame having a fixed jaw and an oscillating lever in the frame having a jaw adapted to coact with the fixed jaw of the frame, the said lever being adjustably mounted in said frame and adapted to be reversed in the same. Furthermore, the means for actuating said lever are so connected to the same as to prevent a rupture in any of the moving parts of the crusher when an object of high resistance is located between the crushing jaws.

The invention consists of the construction and combination of parts to be more fully described hereinafter and fully set forth in the claims.

Reference is to be had to the accompanying drawings forming a part of this specification, in which like characters indicate corresponding parts in all the views and in which:

Figure 1 is a plan view of an embodiment of my invention; Fig. 2 is a section on line 2-2, Fig. 1; Fig. 3 shows the oscillating lever in inverted position; and Fig. 4 shows a modified structure of a connection between the lever and the connecting rod.

Referring to the drawings, 5 represents a frame, in the transverse portion 6 of which is removably positioned a fixed jaw 7. The frame 5 in the longitudinal sides thereof is provided with rectangular apertures 8 and 9 superposing each other and adjacent the said transverse portion 6. Said apertures 8 and 9 extend also through lateral projections 10 and 11 respectively formed on the outer face of each of the sides of the frame 5. Positioned in the apertures 9 are bearing blocks 12 in which is mounted to journal a shaft 13. Mounted rigidly on the shaft 55 is a lever 14, the massive portion 15 of which

receives a jaw 7' similar to the jaw 7 and facing the same. The major part of the lever 14 is cored out and forms a central rib 14', thus lightening the lever without in any way reducing its strength; and the end 60 of the lever remote from where the jaw 7' is removably secured is provided with a recess 16. Fitting snugly into the recess is a projection 17 formed on an arm 18 which is secured to the lever 14 by means of bolts 19 65 positioned in the end of the arm 18 remote from the projections. The bolts 19 project through the lever 14 into the cored-out space. A compression coil spring 20 positioned on each of the bolts maintains the 70 arm 18 in contact with the lever 14. The arm 18 is also provided with a recess 21 at the end where the projection 17 is provided, but on the opposite side, and is engaged by the end of the connecting rod 22. The said 75 rod 22 has a removable portion 23 engaging the recess 21, which can be replaced when the same is worn out, as can be easily seen from the drawings. The crank-shaft 24, positioned in the frame, carries the connecting 80 rod 2.

The end of the lever 14 overhanging the arm 18 is apertured, and therethrough projects a bolt 25, one end of which is positioned in the transverse portion 26 of the 85 frame 5, while the other end projecting above the lever 14 carries a coil spring 27 under compression, normally forcing the lever 14 and the arm 18 therewith in engagement with the connecting rod 22. The projection 17 of the arm, which journals in the recess 16 of the lever, has its center of journal so related to the center of the journal formed between the recess 21 and the connecting rod 22 that the two centers under 90 no circumstances come in a straight line with the center of the crank shaft 24, as can be seen from Figs. 2 and 3. This construction permits the arm 18 to turn on its projection 17 in the recess 16 of the lever when an object of high resistance falls between the jaws 7 and 7' during the movement of the crank shaft 24. That is to say, when such an object is engaged between the jaws the lever 14 remain immovable, while the arm 18, under the action of the connecting rod, will oscillate on the lever 14, causing an alternate compression and relaxation of the springs 20 during its movement. The compressive resistance of the springs 20 is less 110

than the resistance to rupture of the lever 14, so that no damage to any of the moving parts can take place when an object of high resistance is located between the jaws 7 and 5 7' during the movement of the lever.

The bearing blocks 12 carrying the shaft 13, and the bearing blocks 34 carrying the crank shaft 24, are mounted adjustably in respective apertures provided in the frame. 10 The adjustment of these bearing blocks is obtained by means of screws 28 provided in the frame, and also plates 29 fitting into the respective apertures where blocks 12 and 34 are positioned. These plates 29 may be of 15 different thicknesses, so as to permit certain relative adjustments of the shaft 13 and also of the crank shaft 24. As, for example, when the shaft 13 is moved by the screw 28 toward the crank shaft, some of 20 the plates 29 in the aperture 9 are removed from the inner end and placed on the opposite side where the screw 28 is provided. This movement of the bearing blocks 12 toward the crank shaft will permit the 25 crusher to crush the material to a larger size than what is shown at present in Fig. 2. Similarly, if the crank shaft 24 is raised, the upper ends of the jaws 7 and 7' will approach each other and the crusher will admit material of smaller size than that shown 30 in Fig. 2; also, the jaw 7' will move closer to the jaw 7.

In Fig. 3 the lever 14 is shown in inverted position, that is, the bearing blocks 12 of the 35 shaft 13 are positioned in the aperture 8. This necessitates a displacement of the bearing block 34 and also of the bolt 25, the bolt 25 being then positioned in the lower transverse portion 35 of the frame, while the 40 crank-shaft 24 is moved up toward the upper portion of the frame, as shown in Fig. 3. This displacement of the lever 14 permits the crushing of material of large size, that is, of variable sizes from as large as the 45 distance between the plates at the upper portion of the frame, to as small as the distance between the lower ends of the plates, as seen in Fig. 3. While the lever is in the position as seen in Fig. 2, the material 50 crushed will have a size limited by the distance between the plates at the lower end of the same. The bearing block 12 is also mounted adjustably in the aperture 8.

In Fig. 4 a modified structure of the 55 connecting rod 22 is shown, in which case the lever 14 is not provided with an arm 18 but is directly engaged in its recess 16' by a member 30 adapted to oscillate on a connecting rod 31 but which is prevented from the 60 same normally by a coil spring 32 positioned on the bolt 33 secured to the connecting rod 31. In this case when the crushing jaws engage an object of high resistance, endangering the machinery, the member 30 65 will oscillate on the connecting rod 31, caus-

ing the compression of the spring 32, thereby leaving the lever 14, in this case, immovable. As can be seen, the effect is the same in this case as in that previously described, thus preventing injury to the moving parts 70 of the crusher.

The provision of a resilient connection between the moving jaw 7' and the crank-shaft 24 is very important in crushing machines, as the momentum generated in the 75 moving parts of the crusher by the fly-wheels positioned on the crank-shaft 24 would ordinarily rupture some of the moving parts when an object of high resistance is engaged between the jaws and no resilient connection is provided as disclosed in the 80 above specification.

As shown in the drawings, the crushing plates or jaws 7 and 7' have wavy surfaces for crushing, the central portion of which *c* is concave, while the portions *a* and *b* between the ends are convex. The parts *a* and *b* of the jaws will work most and, therefore, the plate will become flat after long service. The convex portions *a* and *b*, in 85 which case, will be worn to the same level as the concave portion *c* of the plate. As described, by means of the adjustment of the bearing blocks, and also by the provision of superposed apertures 8 and 9 in 90 the frame, material can be crushed to a predetermined size when in position shown in Fig. 2, or to a different size when the lever is in position as shown in Fig. 3. This 95 structure gives a large latitude in application.

Having thus described my invention, I 100 claim as new and desire to secure by Letters Patent:

1. In a crusher, a frame; a crushing jaw in 105 said frame; a lever mounted to oscillate in the frame; a crushing jaw carried by the lever; means for oscillating the lever; and means intermediate the lever and said means for oscillating the same whereby the said lever remains immovable when an object of 110 high resistance enters between the jaws.

2. In a crusher, a frame; a crushing jaw in 115 said frame; a lever mounted to oscillate in the frame; a crushing jaw carried by the lever; means for oscillating the lever; an arm between said lever and said means for oscillating the lever; and a resilient member for controlling the movement of said arm between said lever and said means for the 120 purpose set forth.

3. In a crusher, a frame; a fixed jaw in 125 said frame; a lever mounted to oscillate in said frame; a jaw carried by the lever co-operating with the first-mentioned jaw; means for oscillating said lever, said means for oscillating the lever including means whereby the said lever remains immovable when an object of high resistance enters between the jaws.

4. In a crusher, a frame; a jaw removably associated with the frame; a lever mounted to oscillate in the frame; a jaw removably associated with the lever and co-acting with the first-mentioned jaw; means for oscillating said lever, including resilient means whereby said lever remains stationary when an object of high resistance enters between the jaws.
5. In a crusher, a frame; a jaw carried by the frame; a lever mounted to oscillate in said frame; a jaw carried by the lever and adapted to coact with the jaw in the frame; a crank-shaft in the frame; a connecting rod on the crank; means for moving the crank-shaft; and means intermediate the lever and connecting rod whereby when said lever is oscillated by said connecting rod through the medium of said means and an object of high resistance enters between the crushing jaws the said lever remains stationary, and the rupture of said lever, or any other moving part in the crusher, is prevented.
6. In a crusher, a frame; a jaw carried by the frame; a lever mounted to oscillate in said frame; a jaw carried by said lever and coacting with the jaw in the frame; a crank-shaft in said frame; means for actuating the crank; a connecting rod on the crank; means intermediate the lever and said connecting rod, including a resilient member, whereby when said lever is actuated by said crank and a member of high resistance enters between the crushing jaws, the rupture of the lever, or any other moving part of the crusher is prevented.
7. In a crusher, a frame; a crushing jaw carried by the frame; a lever mounted to oscillate in said frame; a crushing jaw carried by said lever and adapted to cooperate with the jaw of the frame; a crank-shaft in said frame; means for actuating the crank-shaft; a connecting rod on the crank; resilient means for maintaining the engagement between the lever and the crank-shaft; and means interposed between the said lever and the connecting rod, including resilient means, whereby when a member of high resistance enters between the crushing jaws a rupture in the lever, or any other moving part of the crusher, is prevented.
8. In a crusher, a frame; a crushing jaw in the frame; a lever mounted to oscillate in the frame; a crushing jaw carried by the lever and coacting with the jaw in the frame, said frame having means whereby the oscillating axis of said lever can be located adjacent either end of the jaw fixed in the frame.
9. In a crusher, a frame; a crushing jaw in said frame; a lever mounted to oscillate in the frame; a crushing jaw carried by the lever; means for oscillating the lever; and an arm resiliently connected to said lever

and positioned intermediate the same and the said means for oscillating the lever, substantially as and for the purpose set forth.

10. In a crusher, a frame; a crushing jaw in the frame; a lever mounted to oscillate in the frame; a crushing jaw carried by the lever; an arm pivotally secured to said lever; means forming a resistance to the pivotal movement of said arm on said lever; a crank-shaft in the frame; a connecting rod on the crank-shaft engaging said arm; means for moving the crank-shaft and whereby said lever is oscillated, said arm being caused to pivot on said lever when the crushing jaws have engaged an object of high resistance, thereby preventing damage to the moving parts of the crusher.

11. In a crusher, a frame; a crushing jaw in the frame; a lever mounted to oscillate in the frame; a crushing jaw in the lever; an arm pivotally associated with the lever; resilient means preventing the pivotal movement of the arm on the lever; a crank in the frame; a connecting rod from the crank to the arm; resilient means from the frame to the lever keeping the engagement between the arm and the connecting rod; means for actuating the crank whereby the lever is oscillated, the resistance of said first resilient means being such as to cause the arm to pivot on the lever when the crushing jaws engage an object of high resistance only, to prevent damage to any of the moving parts of the crusher.

12. In a crusher, a frame; a crushing jaw in the frame; a lever adapted to oscillate adjustably mounted in said frame; a crushing jaw carried by the lever; an arm pivotally associated with the lever; a coil spring normally preventing the pivotal movement of said arm on the lever; a crank-shaft adjustably mounted in the frame; a connecting rod on the crank-shaft in engagement with the arm; resilient means from the lever to the frame whereby the arm is kept in engagement with the connecting rod; means for actuating the crank-shaft, the resistance of said coil spring being such that said arm will only move when an object of high resistance is engaged between the crushing jaws, thereby preventing injury to any of the moving parts of the crusher.

13. In a crusher, a frame; a lever adapted to oscillate positioned in the frame; a crushing jaw on the lever; bearing blocks for said lever; and means for oscillating the lever, said frame having superposed apertures adapted to engage the bearings of the lever and whereby the axis of oscillation of said lever can be changed, substantially as and for the purpose set forth.

14. In a crusher, a frame; a crushing jaw in said frame, said frame having superposed apertures adjacent the jaw; a lever adapted to oscillate in said frame; bearings for said

lever adapted to engage in either of said apertures and whereby the axis of oscillation of said lever can be changed relatively to said jaw; a crushing jaw in the lever adapted to coöperate with the jaw in the frame; means in the frame for oscillating the lever, said frame having means therein whereby the means for oscillating the lever can be adjusted relatively to said lever when the axis

of oscillation of the same is changed, substantially as and for the purpose set forth. 10

In testimony whereof I have signed my name to this specification in the presence of two subscribing witnesses.

AUGUST W. WARSEN.
